United States Patent Office

Des. 192,731

Patented May 8, 1962

192,731

HIGH CHAIR

Harry A. Gelman, Chicago, Ill., assignor to Comfort Lines, Inc., Chicago, Ill., a corporation of Illinois

Filed Apr. 12, 1961, Ser. No. 64,764

Term of patent 14 years

(Cl. D15—1)

FIGURE 1 is a front perspective view of a high chair showing my new design;

FIGURE 2 is a front perspective view thereof with the tray member removed.

FIGURE 3 is a side elevational view;

FIGURE 4 is a rear elevational view; and

FIGURE 5 is a top plan view thereof.

I claim:

The ornamental design for a high chair, substantially as shown.
